W. P. SCHORTMANN

GYRATING TOY

Filed Jan. 27, 1923

Patented June 16, 1925.

1,542,731

UNITED STATES PATENT OFFICE.

WALTER PAUL SCHORTMANN, OF SPRINGFIELD, MASSACHUSETTS.

GYRATING TOY.

Application filed January 27, 1923. Serial No. 615,370.

To all whom it may concern:

Be it known that I, WALTER PAUL SCHORTMANN, a citizen of the United States, residing at Springfield, in the county of Hampden and State of Massachusetts, have invented certain new and useful Improvements in Gyrating Toys, of which the following is a specification.

This invention refers to toys and more particularly those having a mechanism propelled by wind or air currents. It has among its objects to provide a toy of the nature referred to, that can be placed over a radiator or air register and be propelled by the air currents therefrom. Also to have the toy of such a construction that it can be readily assembled or disassembled and compactly packed. Also of such a construction that it will be relatively light yet strong. Other objects will become apparent as the invention is more fully set forth.

This invention consists of the general nature of a merry-go-round having its revolving action brought about by a suitably desired fan blade top adapted to catch air currents flowing vertically upwards, such as those that flow from a radiator or floor register.

In the drawings:

Figure 1 is a view in elevation of a toy embodying this invention.

Figure 2 is a plan view of Figure 1.

Figure 3 is a detail of the see-saw construction.

Similar reference characters refer to similar parts throughout the drawings.

In the construction shown, I represents a roof or top of a toy merry-go-round, and has a fan blade construction 2 that will rotate in the direction of the arrow indicated on the drawings. Its periphery is provided with a suitable fringe or downward pointing rim 3, adapted to catch air or wind coming from underneath and guide it to the fan. This rim also acts as a light fly-wheel and gives the fan stiffness.

The rim is provided with a plurality of pendants 4, arranged to twist and turn as the fan revolves and keep its speed within certain limits, even though the air currents are strong.

The roof or fan top is mounted on a cork or other light element as indicated in dotted lines in Figure 1, and in it is placed a shaft which rotates with the fan. The shaft is shown at 4 and is loosely mounted in the

base 6 of the toy. The upper portion of the shaft is journaled by a bent shaft 7 that is preferably arranged as shown in the drawings. This form is light, yet strong enough to prevent the main shaft from being easily bent over in use.

The main shaft 4 is also provided with an arm 9 that extends out horizontally and makes contact on every revolution with a bent member 10 that connects with a see-saw 11 and actuates the same and causes it to see-saw. The see-saw is overbalanced so that the arm or member 10 will be also in line with the arm 9 as it comes round at every revolution.

The action of the toy is dual in that the revolving of the fan in one plane and the see-saw action in another gives an active looking toy with no apparent motor force to cause its actions.

The base of the toy is provided with concaved legs 12 that enable it to be readily placed on the upper parts of a radiator with security or rested on a flat register.

The see-saw construction is of conventional form and is provided with a ring to assist it keeping the main shaft steady and also locate it positively with reference to its actuating members and arms. The action and function of the toy appear to be evident from the description already given and will not be further outlined.

While but one form of the invention is shown in the drawings it is not desired to limit this application for patent to the particular form shown nor in any other way otherwise than limited by the prior art, as other constructions could be used, employing the same principles and coming within the scope of the appended claim.

Claim.

A toy of the class described comprising in combination, a rotatable fan top horizontally disposed with the greater portion of the extremities of the fan blades non-enclosed except at one tip of each of the blades, a central member for the fan top, a shaft journaled and secured to said member so as to rotate therewith, a horizontally disposed arm extending from the shaft, a see-saw mechanism disposed at the side of the shaft and having one side overbalanced whereby one end of the see-saw will be normally up and the other end normally down, a curved and resilient arm extending upwardly from the see-saw on the side

thereof that is normally down, said arm being extended beyond the center of gravity of the see-saw over to the up side of the see-saw, and whereby the arm of the shaft will engage therewith and swing the see-saw up during one half period of the rotation of the fan and the shaft arm, and

allow the see-saw to swing down during the second half period of the rotation, a fulcrum support for the see-saw and means for bracing the support and the shaft together, and means for holding the support and shaft.

WALTER PAUL SCHORTMANN.
